JOSEPH P. DALY, OF CINCINNATI, OHIO, ASSIGNOR TO THE PROSPERITY COMPANY INC., OF SYRACUSE, NEW YORK, A CORPORATION OF NEW YORK

GARMENT OR IRONING PRESS

Application filed April 29, 1926, Serial No. 105,397. Renewed March 19, 1929.

This invention relates to actuating or power mechanisms including fluid motors for actuating various types of machines, particularly garment pressing and ironing machines and 5 has for its object a construction by which one or both hands of the operator are kept out of danger while the press is being closed and a particularly simple and efficient means for holding the press closed until released by a 10 manual operation.

According to the principles of this invention, it is a broad object to produce a garment or ironing press having motor means which closes the press jaws or the pressing 15 head under compression against the buck, and a novel manual control governs the motor to initiate and continue its power stroke, an outstanding characteristic being that the motor will not continue its forward power 20 stroke unless the operator actually holds down the manual control means till the pressing head reaches a position so nearly closed that insufficient jaw space remains for one to get his fingers or hands in between the press jaws.

25 At this stage of the operation an automatic hold-down control then takes over the manual control, takes it away from the operator, and holds down thereon until the motor reaches ultimate position where the jaws are under 30 final compression on the work. Hence two controls, one a manual and the other an automatic, are coordinated with each other and with the motor, to render safe a high powered jaw-type garment or ironing press.

35 An outstanding feature is that the automatic control does not play its part in the cycle of operation until the press head is so far closed that the operator may then safely remove his hand from the manual control button or lever. He cannot do so before, else the closing motion of the press head will be arrested or will reverse and open up. The invention comprehends a combination pneumatic-mechanical means for locking the press 40 head down, which means is mechanically coordinated with the movement of some part of the motor means or the press, whereby, not until the press head is down, does said means 45 function, and then said means acts automati-

cally to maintain pneumatic or fluid pressure on the motor to hold the press closed.

So also, a broad object is to produce a garment or ironing press, and to produce a safe manually controlled motor means therefor 55 to apply final jaw compression, wherein a two-hand control device must necessarily be manipulated which insures that both hands are away from the press before the jaws make their last movement to produce said pressure. After final compression is attained, or 60 after the press is so nearly closed that insufficient space remains between the jaws for one's fingers, normally inactive lock-down means then automatically functions to thereafter maintain the jaws closed by holding the 65 motor means to its final point of travel; and said lock-down means includes a movable part of the press, and said movable part trips into locking action only after final pressure is 70 reached or only after the space between the jaws is closed, all of which makes for safety in a wide opening large jaw-type high powered garment or ironing press.

According to the concrete embodiment or 75 the one example of the invention shown in the accompanying drawings, it is an object, specifically as to the combined manual and automatic control, to produce a garment or ironing press the jaw or jaws of which are operated 80 by motor means, say a fluid-pressure motor set in operation in this instance by both hands of the operator, and wherein a press-head hold-down valve is mechanically actuated, say 85 opened, only after the press head is so far closed that in case the operator tries to remove one of his hands while the press head is traveling toward the buck, the press head will stop its movement and consequently not close and will even return to its wide open position, but if the operator will keep both hands on the double or two-hand control till the press head 90 is entirely closed, then he may remove his hands and said press will then remain closed because at that time the press-head hold-down 95 valve is positively opened and held open by a mechanical connection whereby fluid pressure is supplied to the motor quite independently of the operator. This mechanical connection itself is actuated by a moving part of the press 100

to open the hold-down valve which otherwise remains normally closed, but that mechanical connection does not become effective or make connection with the hold-down valve to open it until the press head is so nearly closed that an operator cannot get his hand between the jaws, all of which makes for safety in a high-powered air-operated garment or ironing press.

10 A still further object is to provide a four-hand control for a pressing machine motor means, wherein two manuals close the press, a third manual is coordinated with an automatic hold-down control to lock the press closed, and a fourth manual releases all to open the press; and in this way the operator is given control over an automatic control.

15 The invention consists in the novel features and in the combinations and constructions 20 hereinafter set forth and claimed.

In describing this invention, reference is had to the accompanying drawing in which like characters designate corresponding parts in all the views.

25 Figure 1 is a fragmentary vertical sectional view of an actuating mechanism embodying my invention.

Figure 2 is a diagrammatic view of a pressing machine embodying my invention.

30 This actuating mechanism comprises, generally, suitable motor means, here shown as a compressed fluid motor as a cylinder, a movable member or piston in the cylinder, a feed line for a power or motive fluid usually compressed air, a conduit communicating with one end of the cylinder, a control member as a valve interposed between said conduit and the main feed line for controlling the flow of air to the cylinder, manual means for opening 35 the valve, means preferably fluid operated for holding the valve in its operated position and here illustrated as including a conduit preferably connected in the main feed line, a normally closed valve in said conduit and connections arranged in the path of the parts operated by the piston for operating the locking means that is in the illustrated embodiment of my invention thereby opening said valve 40 when the piston has been actuated or the motion transmitting parts actuated thereby a predetermined distance.

45 1 designates the cylinder, 2 the piston movable in the cylinder and having a piston rod 3 connected thereto, which rod is here shown as pivoted at 4 to a motion transmitting part 5 for working a press-jaw such as a head 51 in Figure 2. 6 designates the main feed pipe for the motive fluid as air. The head or upper cylinder end is pivotally mounted on the frame of the press. 7 is the pipe leading to one end of the cylinder, this being usually a combined intake and exhaust pipe.

8 is a valve casing connected in or between 50 a branch 9 of said combined intake and ex-

haust pipe 7, this valve casing 8 having combined intake and exhaust valves therein, that is, a double valve which acts as a unit. 10 designates the intake valve and 11 is the exhaust valve, these being connected by a stem 12. The pipe 7 connects with the valve casing 8 between the valves 10 and 11. A spring 13 or other pressure or yieldable means tends to hold the combined valves 10 and 11 in such position that the intake valve 10 is normally closed and the exhaust valve 11 is normally open.

15 The combined intake and exhaust valves 10 and 11 are manually operated, here shown as by a dual or two-handed control which may be of any suitable form, size and construction. As here shown, this dual control consists of a pair of handles 14 and 15 spaced apart, these handles being shown as levers pivoted at 16 and 17 and being connected by links 18 and 19 to the opposite arms of an evener or equalizing lever 20 pivoted between its ends at 21 to a link 22 connected to a lever 23 pivoted at 24 on a stationary frame part and having an arm 25 thrusting against the end of the operating valve-plunger means or stem 26 of the combined intake and exhaust valves 10 and 11 or against an interposed lever or rocker arm means 27 to be presently described.

20 Each hand or finger lever 14 or 15 is provided with cylindrical shields 28 movable in correspondingly shaped housings 29 and having depressions or finger receiving sockets 30, the shields being provided to prevent the locking down of one of the handles or making difficult the locking down of one of the handles.

25 Returning springs 31 and 32 are interposed between fixed abutments 33 and the levers 14 and 15, these springs 31 and 32 encircling the rods 18 and 19. It will be understood that these handles are pivoted on the frame of the machine provided with this actuating mechanism and that the abutments 33 are part of such frame. 34 and 35 designate fragments 30 of the frame.

35 The operating means for holding the combined intake and exhaust valves 10 and 11 in their operated position as here shown, comprises a diaphragm 36 located in a diaphragm chamber 37, one side of the chamber communicating with the main feed air line 6 and the diaphragm being connected through the other side of the chamber to the pivoted-rocker means or lever 27, the pressure and motion of the diaphragm being transferred to the lever 27 through the plunger 38.

40 Obviously, when the diaphragm 36 is acted upon to thrust the plunger 38 outwardly, the pivoted-rocker means or lever 27 will be locked or held on its pivot or will be held in its position assumed when rocked on its pivot against the stem 26 of the combined intake and exhaust valves 10 and 11 to hold said valves in their manually reset or manually operated po-

sition, that is, the intake valve 10 will be held open and the exhaust valve 11 closed by reason of the lever 27 forced clockwise by the diaphragm 36. The diaphragm chamber 37 is connected to the main feed pipe 6 through branch conduit pipes or tubes 40, 41 and 42.

43 is a press-head hold-down valve casing connecting the branch pipe 42 with the branch conduit section 41, this casing having a normally closed spring pressed hold-down valve 44 therein, which valve is automatically opened through suitable mechanical connections when the piston 2 has traveled a predetermined distance in the cylinder 1. Preferably, this valve casing is so located that the head 45 on a valve stem 45^a thereof is located in the path of a shoulder or operating part 46 on the motion transmitting part or lever 5 in order to be engaged by said shoulder when the part 5 has been actuated to nearly or entirely to its full extent by the piston 2. This press-head hold-down or automatic valve 44 and casing 43 constitute hold-down or lock-down means operated by the motion transmitting means 5 to operate the intake valve locking means 27 by the diaphragm 37 to hold the control valves 10 and 11 in the feed line 9 connected to the motor 1 in their manually operated position so the operator may remove his hand and the press will nevertheless remain closed.

This press is designed to be held closed by air or other fluid pressure and to that end there is provided what may be called non-straightening non-locking operating connections 5 and 49 between the piston rod 3 and press head 51. These lever or link parts 5 and 49 sometimes assume the form of an ordinary toggle, a function of which is frequently to lock or overstraighten after transmitting motion from one element to another. In case a toggle is employed, the arrangement is such that the toggle knee joint or knuckle does not lock or overstraighten and that arrangement is an advantageous one because the press closes and opens more quietly inasmuch as there is no over-forcing of parts into locked position which rattle and vibrate when closed or released. This invention does not pertain to the operating leverage or connection 5—49 itself from the motor to the press head, but pertains to the two-hand control organization, but nevertheless it is invariably preferred that some suitable or conventional type of operating connections be employed in order that all the advantages of this invention may be derived.

The motion transmitting part 5 is usually the power lever of a pressing machine, which lever is pivoted at 47 between its ends to the frame of the machine and connected to a press lever 49 which is pivoted at 50 on to the frame of the machine, which press lever carries a press head 51 movable toward and from the buck 52 of the pressing machine. The shoul-

der 46 and the valve opening head 45 and its stem 45^a thus constitute a delayed or lost motion connection between the part 5 and valve 44, the lost motion of which is taken up when the lever 5 has been actuated by the motor 1 through a predetermined distance. That lost motion is taken up when the head 51 has been moved down so close to the buck 52 that at the time the locking means 27—37 operates, there is insufficient space between the head 51 and the buck 52 large or wide enough to let the operator insert his hands between them after he takes his hand from the handles 14 and 15.

In operation and to close the press, the operator actuates both handle levers 14, 15, thus moving the combined intake and exhaust valves 10 and 11 to open the intake and close the exhaust so that the air is free to enter the cylinder 1, through the pipes 6, 9, 7 and valve casing 8, the operator holding both levers 4 and 15 in manually operated position until the piston in traveling on its out or down stroke causes the shoulder 46 to automatically engage the head 45 at the upper end of the stem 45^a of the valve 44 and open this automatic hold-down valve 44 so that air is free to flow from the main pipe 6 through the pipe sections 42, 41 and 40 to the diaphragm chamber 37 to bulge the diaphragm to move the lever 27 clockwise to hold the combined intake and exhaust valves 10 and 11 in their manually operated position.

Preferably but not necessarily, a manually operated normally closed safety valve 53 is located between the conduit sections 40 and 41, this valve 53 being held closed by a spring 54 and being actuated to open it by a handle lever 55 acting on the outer end of the stem 56 of the valve. The handle 55 is grouped with the handle 15. Thus, in order to lock the press closed by holding down the piston 2, the manual operation of the valve 53 is necessary in order to open it and permit air to flow to the diaphragm chamber 37, and hence the valve 53 really gives the operator control over the function of the automatic valve 44.

To release the air in the cylinder 1 and open the press, a manually operable release valve 57 is provided and this normally closed air-release press-opening valve is located in a casing 58, and is connected by a pipe 59 to the diaphragm chamber 37. The air release valve 57 is spring pressed toward its seat and is operable to permit the air to exhaust or be released from the diaphragm chamber 37 by a handle lever 60 located near and grouped with the handle 14. When the lever 60 is lifted to open the release or exhaust valve 57 as shown, the air exhausts from the diaphragm chamber 37 and permits the spring 13 to close the intake valve 10 and open the exhaust valve 11 thereby resetting these parts to open-press position.

As soon as the combined intake and exhaust

valves 10 and 11 are moved to their normal open-press position so that the exhaust valve 11 is open as shown and the intake valve 10 is closed as shown, the air exhausts from the cylinder through pipes 7, valve casing 8 and past the exhaust valve 11 out into atmosphere through a slot or port in the valve casing 8 shown merely as an example near the exhaust valve head 11 and the press head 51 then 10 opens by reason of a spring or weights which normally urge the press head to open position when the cylinder 1 is free from air pressure.

Should the operator tilt or press down on only one finger lever 14 or 15, then in that 15 event the equalizer 20, which interconnects the two finger levers 14 and 15, merely pivots idly at 21 and does not function to thrust inwardly on link 22 to reset the intake and exhaust valves 10 and 11, and hence fails to 20 close the exhaust valve 11 and open said intake valve 10, and therefore air or fluid pressure does not flow to the motor means 1 and consequently the press head is not closed all of which makes for safety.

25 Another feature or mode of operation worthy of note and which is inherent in this pneumatic press mechanism is that the press attendant cannot start the mechanism in operation and then remove one finger from one of 30 the manual levers or buttons 14 or 15 and expect the press head 51 to continue its downward movement. The movement of the piston 2 immediately stops if either manual 14 or 15 is released before the press-head hold-down valve 44 is opened, and that does not 35 take place till the press head 51 is all the way down and closed under final pressure against the buck 52 and hence no pressure is exerted behind or on the right side of the diaphragm 36 to take the air motor control away from the operator by holding the valves 10 and 11 in press-closed position.

40 Either both hands of the attendant must remain on the manuals 14 and 15 against the pressure of the several springs 31, 32 and 13 till the press jaws 51 and 52 are in pressure contact, or the hold-down valve 44 must be open, in order that the piston 2 remain down to hold the press in closed position on the 45 work. The hold-down valve 44 really takes the place of the attendant's two hands in order that he may remove his hands after the press head is closed without premature opening motion of the press.

50 The foregoing explanation brings one to a better understanding of the safety features inherent in the mechanism shown in the drawing and it may be referred to as the delayed locking or delayed pressure means because the locking or holding down of the piston 2 and hence the press head 51 is delayed until the press-head hold-down valve 44 is opened. That delay renders safe the press because by that delay an attendant's hand or 55 hands is safe even though he may too quickly

start the press head and then change his mind to smooth out a wrinkle or reposition the work and he may carelessly put one or both hands in the jaws to do so, whereupon the head 51 stops or returns to up position because the air 70 instantly stops flowing into the cylinder and instantly exhaust therefrom.

In further explanation of another feature in the valve 53, it is noted that said valve 53 is an additional safety element introduced into the air line 40-41, and its handle 55 may be lifted by the attendant's forefinger after the valve 44 is automatically opened by the lug 46 in order that motive fluid pressure may actually pass into the line 40 and hence bulge 80 out the diaphragm 36 to work the lever 27 for the purposes ascribed thereto. This valve 53, in the position shown, positively shuts the tube 41 unless the handle 55 is up to unseat the valve disc 53 against the air pressure and the 85 spring holding said disc closed.

The valve 53 is not used in all instances and hence the two tubes 40 and 41 may as well be directly connected and the press is then just as safe in all respects because it is the hold-open valve 44 and its inaction till the press jaws 51 and 52 are closed that really matters and makes for safety. This valve 53 and its handle 55 actually gives the operator control 90 over the automatic means 45-46 and compels the use of his hand away from the jaws before the press will lock down.

The lost motion or disconnection between the lug 46 and valve head 45 is the arrangement which delays locking the combined intake and exhaust valves 10 and 11 open and closed, respectively, until it is safe to do so, but that arrangement does not in the least interfere with the down motion of the head if the attendant keeps both of his hands 100 on both manuals 14 and 15.

105 It is to be appreciated that the mere example of the means shown in the coordinated valve 45 and trip or release lug 46 is to disclose an underlying broad principle and several different equivalent species of construction are possible without departing from the scope of this invention.

The aggroupment of the four control buttons or levers 14, 15, 55 and 60 is a noteworthy 110 feature, there being two manuals 14 and 15 to initiate the motor down stroke motion to close the press head, a third manual 55 to let air pass from tube 41 to 40 and hence to diaphragm 36 to hold exhaust valve 11 closed and intake valve 10 open so that the piston 2 will remain down to hold the press head closed, and a fourth release manual 60 to open the press by exhausting the air pressure from the cylinder 1. For clarity, the press-opening valve 57 and its manual 60 are called the 115 release means or valve to distinguish it from the normally open exhaust valve 11.

120 The valve 53 and its manual 55 may be omitted as heretofore explained, this being 125

accomplished merely by connecting the two tubes 40 and 41. However in some press constructions, this second press-head hold-down valve 53 is desirable for super safety and accordingly I have provided for such requirements.

The two coordinated press-head hold-down valves 44 and 53 must both be opened to maintain the piston 2 down by air pressure and hence hold the press head 51 under compression against the buck 52 by air pressure. The hold-down valve 44 is of course opened automatically by the motor driven trip device 46 and the other valve 57 is opened manually. If the manual hold-down valve 53 is not present in the general combination, there is nothing else to be done by the press attendant after the valve 44 automatically opens. For extra safety the attendant must manually let air by valve 53 to the diaphragm chamber 37. If he does not do so, the press head will throw open in the same way that the head throws open if the operator tries to remove one hand from one manual 14 or 15 while the head is traveling downwardly. The operator can easily reach the super-safety hold-down manual 55 with his forefinger while he holds down on the adjacent manual 15 with his other finger, and thereby the several manual operations are coordinated.

Of further significance is the placement of the manual 55, which actuates the valve 53, right under the finger socket 30 so that when the latter is depressed, but not before, can the operator reach the manual 55 with his forefinger and lift the manual 55 to admit a shot of air to the diaphragm 36 to lock the valve-means 10-11 to that position to which the valve-means 10-11 were set manually when both finger sockets 30 in manuals 14 and 15 were depressed. Hence the press head is safely locked down manually by disposing the manual or lock-down lever 55 beyond reach until the manual 15 is down. The combined and separate utility of the valves 44 and 53, one or the other or both, has now been fully explained.

What I claim is:

1. An actuating mechanism comprising a cylinder, a piston movable in the cylinder, a main feed line for a motive fluid, a valve for controlling the flow of motive fluid from the feed line to the cylinder, manual means for opening the valve, fluid operated means for holding the valve in open position, a conduit connecting the fluid operated means with the feed line, a normally closed valve in the conduit, and operating means for the last mentioned valve arranged to be actuated when the piston has traveled a predetermined distance in the cylinder.

2. An actuating mechanism comprising a cylinder, a piston movable in the cylinder, a main feed line for a motive fluid, a valve for controlling the flow of motive fluid from

the feed line to the cylinder, manual means for opening the valve, fluid operated means for holding the valve in open position, a conduit connecting the fluid operated means with the feed line, a normally closed valve in the conduit, operating means for opening the last mentioned valve arranged to be actuated when the piston has traveled a predetermined distance in the cylinder, a normally closed manually operable valve in said conduit between the former valve therein and the fluid operated means, and means for releasing the fluid operated holding means.

3. An actuating mechanism comprising a cylinder, a piston movable in the cylinder, a main feed line for a motive fluid, an intake valve for controlling the flow of motive fluid from the feed line to the cylinder, manual means including a handle for opening said intake valve, fluid operated means for holding the intake valve in open position, a conduit connecting the fluid operated means with the feed line, a normally closed hold-down valve in the conduit, operating means for opening the hold-down valve arranged to be actuated when the piston has traveled a predetermined distance in the cylinder, a normally closed manually operable valve in said conduit between the hold-down valve and the fluid operated means, and a handle for operating the last named valve, said handles being grouped together for the operator's convenience.

4. An actuating mechanism comprising a cylinder, a piston movable in the cylinder, a combined intake and exhaust pipe connected to the cylinder, a feed pipe for a motive fluid, a valve casing interconnected between the combined intake and exhaust pipe and the feed pipe, a normally closed intake valve and a normally open exhaust valve combined together and operatively mounted in the casing, manual means for operating the combined intake and exhaust valves to open the intake and close the exhaust including a handle, fluid operating means for holding the combined intake and exhaust valves in operated position, a conduit communicating with said fluid operating means and with the feed pipe, a normally closed hold-down valve in the conduit, and connections arranged to be operated by the piston when the piston has traveled a predetermined distance on its power stroke to open said normally closed hold-down valve.

5. An actuating mechanism comprising a cylinder, a piston movable in the cylinder, a combined intake and exhaust pipe leading to one end of the cylinder, a feed pipe for a motive fluid, a valve casing connected with said feed pipe and with said combined intake and exhaust pipe, a normally closed intake valve and a normally open exhaust valve combined together and operatively mounted in the casing, manual means for operating

- the combined intake and exhaust valves to open the intake and close the exhaust including a handle, fluid operated means for holding the combined intake and exhaust valves in operated position, a conduit communicating with said fluid operating means and with the feed pipe, a normally closed hold-down valve in the conduit, connections arranged to be operated by the piston when the piston has traveled a predetermined distance on its power stroke to open said normally closed hold-down valve, a second normally closed valve in said conduit, manual means for opening the second normally closed valve including a handle grouped with the former handle, and a normally closed manually operated release valve for exhausting fluid pressure from the fluid operated means and from the cylinder.
5. An actuating mechanism comprising a cylinder, a piston movable in the cylinder, a combined intake and exhaust pipe connected to one end of the cylinder, a feed pipe for the motive fluid, a valve casing connected with said feed pipe, a normally closed intake valve and a normally open exhaust valve combined together and operatively mounted in the casing, the combined intake and exhaust pipe being connected to the valve casing to be controlled by both valves, manual means for operating the combined intake and exhaust valves to open the intake and close the exhaust including a handle to feed motive fluid to the cylinder, fluid operating means 35 for holding the combined intake and exhaust valves in operated position, a conduit communicating with said fluid operating means and with the feed pipe, a normally closed hold-down valve in the conduit, connections arranged to be operated by the piston when the piston has traveled a predetermined distance on its power stroke to open the hold-down valve, a second normally closed valve in said conduit including a handle grouped with the former handle and to open the second normally closed valve, an exhaust pipe leading from said fluid operated means, and a manually operable normally closed release valve in said pipe to exhaust the motive fluid from said cylinder.
- 40
6. An actuating mechanism comprising a cylinder, a piston movable in the cylinder, a main feed line for a motive fluid, an intake valve for controlling the flow of motive fluid to and from the cylinder, a handle for operating said intake valve, fluid operated locking means for holding the intake valve in the position to which it is operated by the handle, a manually operated normally closed release valve for releasing the flow of motive fluid from the fluid operated means, and automatic valve means operated by the movement of the piston for controlling the flow of motive fluid to the fluid operated holding means.
- 45
7. An actuating mechanism comprising a cylinder, a piston movable in the cylinder, a main feed line for a motive fluid, an intake valve for controlling the flow of motive fluid to and from the cylinder, a handle for operating said intake valve, fluid operated locking means for holding the intake valve in the position to which it is operated by the handle, a manually operated normally closed release valve for releasing the flow of motive fluid from the fluid operated means, and automatic valve means operated by the movement of the piston for controlling the flow of motive fluid to the fluid operated holding means.
- 50
8. In an actuating mechanism for garment
- or ironing press jaws having an opening and closing movement, the combination of a cylinder, a piston movable in the cylinder, a feed line for a motive fluid, valve means for controlling the flow of motive fluid to the cylinder, two-hand control manual means for operating the valve means, means tending to reset the valve means in its initial position, motion transmitting means connected to a movable press jaw and to the piston to be actuated thereby, locking means for holding the valve means in operated position, and mechanically-operated means operated by the motion transmitting means to actuate the locking means to hold the valve means in operated position to hold the press jaws closed.
- 55
9. In an actuating mechanism for pressing and ironing machines having a jaw opening and closing movement, the combination of a cylinder, a piston movable in the cylinder, a feed line for a motive fluid, valve means for controlling the flow of motive fluid to the cylinder, manual means for operating the valve means, means tending to reset the valve means to its initial position, motion transmitting means connected to the piston to be actuated thereby, locking means for holding the valve means in operative position, mechanically-actuated means operated by the motion transmitting means to actuate the locking means to hold the valve means in operated position to hold the press jaws closed, and operator-operated means for unlocking the locking means.
- 60
10. In an actuating mechanism for pressing and ironing machines having a jaw opening and closing movement, the combination of a cylinder, a piston movable in the cylinder, a feed line for a motive fluid connected to the cylinder, valve means for controlling the flow of motive fluid to and from the cylinder, manual means for operating the valve means, means tending to reset the valve means to initial position, motion transmitting means connected to the piston to be actuated thereby and to effect the jaw opening and closing movement, locking means for holding the valve means in operated position, mechanically-actuated means operated by the motion transmitting means to operate the locking means to hold the valve means in operated position, and operator-operated means for unlocking the locking means, the mechanical actuated means comprising a lost motion connection arranged to be taken up when the motion transmitting means has been actuated a predetermined distance by the piston to effect the jaw closing movement.
- 65
11. In an actuating mechanism for pressing or ironing machines having an opening and closing movement, the combination of a motor having a movable member, a feed line for a motive power, control means for initiating the flow of motive power to the motor,

5 manual means for operating the control means, a means tending to return the control means to initial position, motion transmitting means connected to the movable member of the motor to be actuated thereby, means for locking the control means in operated position, mechanically-actuated means operated by the motion transmitting means to hold the control means in its operated position, and operator-operated means for releasing the locking means.

10 12. In an actuating mechanism for pressing or ironing machines having a jaw opening and closing movement, the combination of a motor means having a movable member, a feed line for a motive power, means for controlling the flow of motive power to the motor, manual means for operating the controlling means, means tending to return the 15 controlling means to initial position, motion transmitting means connected to the movable member of the motor to be actuated thereby, means for locking the controlling means in operated position, means operated by the motion transmitting means to hold the controlling means in its operated position, and operator-operated means for releasing the locking means, the locking means comprising a lost motion connection arranged to be taken 20 up after the motion transmitting means has been actuated a predetermined distance.

25 13. In an actuating mechanism for machines having an opening and closing movement, the combination of a motor means having a movable member, a feed line for a motive power, means for controlling the flow of motive power to the motor, manual means for operating the controlling means, means tending to return the controlling means to 30 initial position, motion transmitting means connected to the movable member of the motor to be actuated thereby, means for locking the controlling means in operated position, means operated by the motion transmitting means to hold the controlling means in operated position including normally spaced apart shoulders forming a lost motion connection, one shoulder being movable with the motion transmitting means and movable 35 toward the other shoulder to take up the lost motion when the motion transmitting means has travelled a predetermined distance, and operator-operated means for releasing the locking means.

40 14. In a garment or ironing press, coacting press jaws, operating mechanism connected with one of the jaws to open and close the press including motor means, means including a motive energy line having a two-hand control device in said line to safely supply motive energy to the motor means to close the press and to also cause the movable jaw to stop its closing motion in case an operator carelessly removes one hand from the two-hand control device before the jaw reaches

its closed position; jaw lock-down means co-operating with the operating mechanism to hold the movable jaw closed under pressure so as to enable the operator to remove his hands from the control device and also 45 acting to hold said operating mechanism against reverse motion; mechanically-actuated means operated by the operating mechanism only after the press is closed to initiate the aforesaid action of the jaw lock-down means; and a manually-operable release means to remove the pressure from said jaw lock-down means to allow the operating mechanism to reverse its motion to open the press and to return the mechanically-actuated means to normal press-open position.

50 15. In a garment or ironing press, coacting press jaws, operating mechanism connected with one of the jaws to open and close the press including a fluid motor, a fluid-pressure line including a manually-operable normally-closed inlet-valve means connected with the fluid motor to admit fluid pressure thereto for operating the fluid motor in one direction to close the press, and also including a manually-operable normally-open exhaust valve means which must be closed to direct said fluid pressure into the motor and being spaced from the inlet-valve means, two spaced safety manuals to work the two valve 55 means, means to hold the press closed under pressure including mechanically-actuated means actuated by the operating mechanism to prevent reverse motion of the fluid motor only after the press is closed to hold the jaws 60 under pressure and thus relieve the operator so he may turn loose of both valve means, and an air-release means having a manually operable handle therefor to release the means which holds the press closed whereby the operating mechanism may reverse its motion to relieve the jaw pressure and open the press.

65 16. In a garment or ironing press having coacting press jaws, a fluid-pressure motor and operating connections therefrom to a jaw to open and close the press, a fluid-pressure line to supply motive fluid to the motor, intake-valve means held normally closed in the fluid line including a two-hand control manual means to open said intake 70 valve means to close the press jaw, press-jaw lock-down means including mechanically-actuated means operated by movement of the motor and its operating connections after a predetermined distance has been traveled 75 by the press jaw to lock the intake-valve means open so as to lock the jaw closed under pressure by reason of maintaining fluid pressure in the motor so as to relieve the operator of holding the manual means after the press is closed, said mechanically-actuated means having a delay operating engagement effective only after the press is closed 80 to lock the intake-valve means open, and air- 85

release means to exhaust the motive fluid from the motor to open the press.

17. In a garment or ironing machine having press jaws, a movable member connected with a jaw to open and close the press, a fluid motor having a cylinder and piston and operating connections therefrom to the movable member, a fluid-pressure line connected to the motor to supply motive fluid thereto, an intake valve normally closing off the fluid line to the motor, an exhaust valve normally opening to atmosphere the fluid line to the motor, means including spaced manuals to open the intake valve and close the exhaust valve to start the motor, a press-jaw hold-down valve in the fluid line, means operated by fluid pressure allowed to pass said press-jaw hold-down valve to maintain the intake valve open and exhaust valve closed to maintain motive-fluid pressure on the piston after the manuals are released, mechanical-operating connections actuated by the movable member to engage and open the press-jaw hold-down valve to automatically take the manual control away from the operator after the press is closed, and means to open the press including handle means to exhaust that motive fluid from the cylinder supplied thereto after the manuals were released by an operator.

18. In a garment or ironing press having jaws, operating means therefor including a fluid-pressure motor, a fluid-pressure supply and valve-control means therefor connected to the motor including a manual valve yieldable means urging the manual valve to closed position, a handle by which an operator opens the manual valve against the yieldable means to admit motive fluid to motor to close the press, locking means to hold the manual valve in locked open position after the motor completes its stroke to maintain fluid pressure in the motor to hold the press closed, a normally-closed automatic valve to control the locking means to lock the manual valve open as aforesaid, means operated by the motor at the end of its stroke to automatically lock the locking means and thus relieve the operator of hold the handle after the press closes, and release means to unlock the locking means so as to allow the return of the valve-control means to normal open-press position and the discharge of the motive fluid from the motor to open the press.

19. In a garment or ironing press, coacting jaws, operating means connected with a jaw to open and close the press including a fluid motor, a fluid-pressure line including a normally-closed intake valve connected with the fluid motor, yieldable means acting against the valve to hold it closed, a handle for the operator to overcome the yieldable means to open said intake valve and admit fluid pressure to the motor to close

the press, a pressure-actuated locking means to lock open said intake valve against the yieldable means and connected to the fluid pressure line, a normally-closed automatic valve in the fluid-pressure line, means actuated by the operating means only after the press is partly closed to engage and hold open the normally-closed automatic valve to actuate said locking means to overcome said yieldable means and hence relieve the operator from holding the handle, and a normally-closed manually-operable valve in the fluid-pressure line between the automatic valve and the intake valve and which is opened by the operator after the press is closed to render effective said locking means.

20. In a garment or ironing press having jaws, operating means attached to a jaw including a fluid motor to close the press, a fluid line connected to the motor, a coordinated automatic and manual control means for the motor including three valves in the fluid line, one valve being an intake valve to admit a motive fluid to the cylinder to actuate it in one direction to close the press and a handle for opening this intake valve against a yieldable means which is provided to normally hold closed said intake valve, a normally closed second valve being an automatic valve and adapted to supply fluid pressure to a valve-locking device to lock open the intake valve, means actuated by the motor at the end of its stroke to open the automatic valve only after the press is closed, a third valve operatively related with the automatic valve and with the valve-locking device and normally rendering the latter ineffective by closing of the pressure released by the automatic valve, a handle attached to the third valve for opening the latter by the operator to now render effective the automatic valve and the valve-locking device whereby the intake valve is now locked open and consequently fluid pressure is maintained in the motor to hold the press jaw closed, and release means to discharge the fluid pressure from the motor to open the press and to return the several valves and valve-locking device to normal press-open position.

21. In a garment or ironing press having jaws, operating means attached to a jaw including a fluid motor to close the press, a fluid line connected to the motor, a combined automatic and manual control means for the motor including four valves in the fluid line, one valve being an intake valve to admit motive fluid to the cylinder to actuate it in one direction to close the press and a handle for opening this valve against a yieldable means which is provided to normally hold closed said intake valve, a normally closed second valve being an automatic valve and adapted to supply fluid pressure to a valve-locking device to lock open the intake valve, means actuated by the motor to open the automatic

valve only after the press is closed, a third valve operatively related with the automatic valve and with the valve-locking device and normally rendering the latter ineffective by shutting off the pressure released by the automatic valve, a handle attached to the third valve for opening the latter by the operator to now render effective the automatic valve and the valve-holding device whereby the intake valve is now locked open and consequently fluid pressure is maintained in the motor to hold the press jaw closed, a fourth valve adapted as a release and press-opening means and being connected with the valve-locking device aforesaid, and a handle attached to this fourth valve to open the latter to discharge pressure from the valve-locking device whereby the intake valve is now closed and fluid pressure is discharged from the cylinder so as to allow the press to open.

22. In a garment or ironing press, jaws and fluid-pressure motor means to operate one of the jaws, a pressure-feed line to supply motive fluid to the motor, motor-control means in the feed line including four valves and four handles, one of the valves being a normally-closed intake valve, two of the handles comprising a two-handle safety control and means operatively connecting these two handles to the intake valve to open said intake valve to close the press by compelling an operator to use both hands, a second valve normally closed and automatic means operated by the motor after the press is closed to automatically open this second valve, fluid-operated valve-locking means connected with the second valve and actuated by motive fluid passing this second valve to hold the intake valve open after the press is closed so the operator may remove both hands and the press will remain closed on the work between the jaws, a third normally-closed valve having a third handle and being interposed between the normally-closed second named valve and the fluid operated valve-locking means and by which the motive fluid which passes by the second named valve cannot reach the fluid-operated valve-locking means until said third normally-closed valve is opened by the third named handle grasped by the operator so that manual control is established over the second valve, and press-opening means including a fourth normally-closed release valve having a handle to open it and being connected to the fluid-operated valve-locking means to discharge the motive fluid therefrom and to exhaust the motor.

23. In a garment or ironing press, jaws and operating means therefor to open and close the press including a motor having a piston and cylinder operatively connected to a jaw, a fluid line connected with the cylinder, an intake valve in the fluid line, yieldable means acting against the intake valve to hold it normally closed, manual means connected

with the intake valve by which an operator opens and holds said intake valve against the yieldable means aforesaid whereby motive fluid is admitted to the cylinder to drive the piston to one end thereof to close the press; means under the control of the operator, and effective only after the press closes, for causing the operating means including the motor to take over the holding open of the intake valve at the end of the piston stroke to maintain the motive-fluid pressure in the cylinder aforesaid and to hold the press jaws closed so that the operator may release his hands from the manual means and yet the press will remain in closed position; and release means to open the press.

24. In a garment or ironing press, jaws and operating means therefor to open and close the press including a motor having a piston and cylinder operatively connected to a jaw, a fluid line connected with the cylinder, an intake valve in the fluid line, yieldable means acting against the intake valve to hold it normally closed, manual means such as a handle connected with the intake valve by which an operator opens it against the yieldable means aforesaid whereby motive fluid is admitted to the cylinder to drive the piston to one end thereof to close the press, fluid-operated means operatively connected with the intake valve to hold it open to maintain fluid pressure in the cylinder after the press is closed, a tube to supply fluid pressure to said fluid-operated means, a normally-closed valve in said tube which renders inoperative the fluid-operated means, manual means such as a second handle for the last named normally-closed valve to open the same to admit motive fluid to the fluid-operated means to hold the intake valve open independently of the operator and hence enable him to remove his hand from the first named handle without the press opening up, and release means for exhausting the motive fluid from the cylinder and from the fluid-operated means thereby enabling all correlated parts to return to normal press-open position.

25. In a garment or ironing press, coacting jaws and fluid-pressure motor means to operate the press, a control for starting the motor means including an intake valve connected to the motor to admit motive fluid thereto, yieldable means to hold the intake valve closed, a manual to open the valve against said yieldable means, a fluid-operated means to hold the intake valve open against the yieldable means when the manual is released, a single housing containing the intake valve and the fluid-operated means, a pivoted lever operatively interposed between and engaging the intake valve and the fluid-operated means and through which lever the intake valve is held open by said fluid-operated means, operating connections from the manual to the pivoted lever, and release means

- to open the press including a release valve connected with the fluid-operated means to exhaust the motive fluid from the fluid-operated means whereby the aforesaid yieldable means returns the intake valve to normally closed position and the motive fluid is exhausted from the motor means.
26. A garment or ironing press comprising coacting press jaws, operating mechanism including a lever and fluid motor having a cylinder and piston connected with one of the jaws to open and close the press, a fluid-pressure line including a manually-operable normally-closed inlet-valve means connected to the fluid motor cylinder to admit fluid pressure thereto for driving said piston in one direction to close the press, and also including a manually-operable normally-open exhaust-valve means which must be closed to direct said fluid pressure into the cylinder and being spaced from the inlet-valve means, plunger means operatively connecting the two spaced-valve means, two spaced-safety manuals requiring the simultaneous use of both hands of an operator, operating connections provided between the two spaced-safety manuals and the plunger means whereby both valve means may be simultaneously moved to reverse their positions to open the inlet-valve means and close the exhaust-valve means by depressing the manuals to feed fluid pressure to the cylinder, spring means cooperating with and tending to return the operating connections to normal open-press position and also tending to hold the inlet-valve means in normally-closed position and the exhaust-valve means in normally-open position whereby the press remains normally open, pivoted-rocker means operatively engaging the plunger means, and means for urging the pivoted-rocker means in engagement with the plunger means including an operating part carried by the lever and an actuated element having delayed engagement with said operating part whereby the two spaced-valve means are held to their manually-operated closed-press position to maintain the fluid pressure against the piston to hold the press closed by fluid pressure after the operator removes his hands from the manuals, said means operating thru the delayed engagement aforesaid to render said means completely inoperative until after the piston travels a predetermined distance to close the press, and means to exhaust the fluid pressure from the motor to open the press.
27. A garment or ironing press comprising coacting press jaws, operating mechanism including a lever and a fluid motor connected to said lever and to one of the jaws to open and close the press, a fluid-pressure line including a valve having a normally-closed intake port and a normally-open exhaust port connected to the fluid motor to admit fluid pressure thereto for driving the motor in one direction to close the press and to exhaust the fluid pressure from the motor when said valve is in another position to allow the press to open, two spaced-safety manuals requiring the use of both hands of an operator, operating connections provided between the two spaced-safety manuals and the valve whereby the valve is manually set to reverse position to open the intake port and close the exhaust port by movement of both manuals to feed fluid pressure to the motor, spring means cooperating with and tending to return the operating connections to normal open-press position and also tending to hold the intake port normally closed and the exhaust port normally open, a rocker operatively engaging the valve, means for urging the rocker against the valve including an operating part swingable with the lever and an actuated element having a delayed motion in respect to said operating part whereby said rocker engages the valve to hold it in the manually reversed position aforesaid to maintain the fluid pressure in the motor after the operator removes his hands from the manuals, and said means operating thru the delayed motion to render the rocker completely inoperative until after the fluid motor travels a predetermined distance to close the press, whereupon the motor is then effective to hold the press closed under fluid pressure and is also effective thru said means to hold the exhaust closed and the intake open during the pressing operation, and means to exhaust the fluid pressure from the motor to open the press.
28. In a garment or ironing press having a coacting press head and buck, a fluid-pressure motor having a piston and non-straightening non-locking operating connections therefrom to the press head to open and close the press, a fluid-pressure line to supply a motive fluid pressure to the motor, intake-valve means held normally closed in the fluid line and two spaced-safety manuals to open said intake-valve means to admit fluid pressure to the motor to close the press head, means to arrest or stop the downward travel of the press head and restore the two safety manuals to open-press position in event an operator releases one or both safety manuals before the press closes; and press-head hold-down means, including mechanically-actuated valve means opened by movement of the motor at the end of the piston stroke, to hold the press head down by fluid-pressure exerting a yielding force thru the non-straightening non-locking operating connections by reason of maintaining the motive fluid at line pressure against the piston, and to relieve the operator of holding the two spaced-safety manuals after the press is closed; said mechanically-actuated valve means having a delayed action and therefore being effective

In testimony whereof, I have hereunto signed my name, at Syracuse, in the county of Onondaga, and in the State of New York, this 22nd day of April, 1926.

JOSEPH P. DALY.

only after the press is closed to hold the mechanically-actuated valve means open, and means to release the pressure from the motor to open the press.

29. A garment or ironing press comprising a coacting press head and buck, a fluid-pressure motor having a piston, operating connections from the piston to the press head to close it onto the buck, a fluid-pressure supply conduit and a normally-closed inlet valve connected with the motor, two spaced-apart safety manuals having a connection means with the normally-closed inlet valve and requiring the use of both hands to open said inlet valve to admit fluid pressure to the motor to drive the piston in one direction to close the press, means to interrupt the flow of fluid pressure to the motor and return the safety manuals to normal open-press position and thereby arrest the closing movement of the press head in event an operator releases one or both of the safety manuals before the press head reaches the buck, means operating only after the press head has reached the buck to maintain the fluid-pressure motor open in direct communication with the fluid-pressure supply conduit so that the operator may then release the safety manuals, said last named means including a delayed-action valve opened only at the end of the piston stroke, and means to release the fluid pressure from the motor at the end of the pressing operation to open the press.

30. A garment or ironing press comprising a coacting press head and buck, a fluid motor having a piston connected with the press head to close the press and hold it closed under resilient fluid pressure continuously applied to the piston during the pressing operation, press-opening means urging the press head toward open position after the fluid pressure is released from the cylinder, a normally-closed inlet valve connected with the motor, a pressure feed line connected to the inlet valve, two spaced manual control means having a connection means with the inlet valve to open it and admit pressure to the motor to drive the piston on its out stroke, means acting on the spaced manual control means to restore them to normal open-press position when released by the operator and to stop the flow of pressure to the motor in event said release of the manual control means occurs during the travel of the head toward the buck; and means, including a mechanically-actuated valve, operated only after the press head has reached the buck, to continue the application of pressure to the motor in order that the operator may then release the manual control means; and fluid pressure release means to exhaust the motor at the end of the ironing or pressing operation in order that the press-opening means restore the press to normally open position.
